LEG SUPPORT AND RESTRAINING DEVICE

Emma J. Wiruth, Tulsa, Okla.

Application January 22, 1936, Serial No. 60,337

7 Claims. (Cl. 311—11)

This invention relates generally to the practice of surgery and is concerned primarily with the production of a device for supporting the lower limbs of a patient while in a recumbent position on an operating table or the like.

An object of the invention resides in the provision of a leg supporting device which is adjustable to various positions best suited to the size of the patient thus providing for maximum comfort and facilitating the performance of the operation.

Another object of the invention consists in the provision of such a device which is capable of firmly securing the entire leg from just above the knee to the foot thereby avoiding any possibility of the leg being worked free from the support and consequent interference with the operation being performed by the operator.

A further object of the invention resides in constructing a leg support for the major portion of the leg and which is easily adjustable as to length so as to be readily adaptable to the requirements of the various patients.

A still further object of the invention consists in providing a leg support which is light in weight, yet strong and durable in construction and capable of being quickly applied to or removed from an operating table.

Other objects and advantages of the invention will be apparent from the following description when taken in connection with the accompanying drawing, in which,

Figure 1 is a perspective view of an end of a conventional operating table showing one of the leg supports mounted thereon and a second one indicated in dotted outline.

Figure 2 is a fragmentary sectional view of one of the supports, and

Figure 3 is a transverse sectional view taken on line 3—3 of Figure 1.

Referring to the drawing in greater detail, the numeral 1 indicates an operating table, on the end of which is mounted a pair of vertically extending eyes or sockets 2 provided with set screws 3. These eyes are adapted to receive and adjustably support rods 4 provided with offset portions 5 adapted to properly space the leg supports from the end of the table.

The upper end of each of the rods 4 is provided with a pair of perforated ears 6 adapted to receive between them a perforated ear 7 formed on each of the leg supports. A pin or screw 8 is passed through the aligned perforations and completes the hinged connection which permits the leg support to pivot in a vertical plane. Inasmuch as

the construction of the leg supports is identical, only one of them will be described in detail.

The main body of the leg support carries the hinge ear 7 and is indicated by the numeral 9. This portion of the support is substantially U-shaped in cross-section and is provided with a bend intermediate its length adapted to conform to the back of the patient's leg with the knee slightly bent. This portion of the support, as well as that about to be described, is preferably made of chromium or other bright metal, although it will be understood that aluminum or other suitable metal may be employed, and is provided with cut-out portions 10 to reduce the weight of the complete device.

The under side of the part 9 adjacent its forward end is provided with a lug 11 in which is fixed a guide rod 12 for a purpose to be described, and formed on the inner sides of this portion of the support are rectangular guideways 13 formed by pressing sections of the metal outwardly.

The second section of the leg support comprises a member 14, substantially U-shaped in cross-section and provided with a foot-rest 15. This section is telescopically received in the main section 9. On the exterior sides of member 14, at the upper end thereof, are elongated lugs 16 seated in the guideways 13, and it will be apparent that the section 14 may be adjusted longitudinally of section 9 by reason of the sliding connection between the lugs and guideways. Set-screws 17 are provided for locking the section 14 in its various adjusted positions.

While the lugs 16 and set-screws 17 serve to prevent the rotation of section 14 and lock it against longitudinal movement to a certain extent, supplemental means are provided to insure the maintenance of the proper relationship between these parts. To this end the back of section 14 is provided with a pair of lugs 18 and 19 threaded onto the guide rod 12, and set-screws 20 carried by the lugs serve to lock them to the rod at the desired position. It will be apparent therefore that section 14 is secured against longitudinal movement by two pairs of set-screws 17 and 20 and is held against rotative movement by the lugs 16 in guideways 13 and lugs 18 on guide rod 12.

Adjacent the longitudinal edges of the sections 9 and 14 of the leg support slots 21 are provided to receive straps (not shown) for firmly and securely strapping the patient's legs, ankles and feet to the supports.

In the operation of the device, the leg supports are raised or lowered, as best suited to the partic-

ular patient, by loosening the set-screws 3 and adjusting the vertical positions of the rods 4 with respect to the eyes 2. The section 14 is then adjusted longitudinally of section 9 to a length 5 identical with that of the patient's leg from the knee to the foot. The leg is then strapped to the support at the various points provided by the slots 21. The pivotal connections 8 between the leg supports and rods 4 permit the supports to be 10 rocked to positions providing the greatest comfort to the patient and yet securely maintaining the legs strapped to the supports.

From the foregoing description and the attached drawing it will be apparent to those skilled 15 in the art that I have devised a simple and inexpensive leg support and holder; that it is readily adjustable to suit the sizes of various patients; that it provides means for firmly securing the legs from just above the knee to the foot, thereby 20 avoiding any possibility of accidental displacement of the legs from the supports; and that while strong and durable, the supports are relatively light in weight and capable of easy handling by a single operator.

25 In accordance with the patent statutes I have described what I now believe to be the preferred embodiment of the invention but inasmuch as various minor changes may be made in the details of construction without departing from the 30 spirit of the invention, it is intended that all such changes be included within the scope of the appended claims.

What I claim is:

35 1. A leg support and restraining device including a vertically adjustable rod, a leg support pivotally mounted thereon and adapted to support a patient's leg from the knee to the foot, said support comprising telescopically engaged sections of substantially semi-circular cross-section, and 40 means for locking the sections in various adjusted positions.

2. A leg support and restraining device including a rod, a leg support pivotally mounted thereon, said support comprising a plurality of sections substantially semi-cylindrical in cross-section, and means for adjusting said sections to vary the 45 length of the support.

3. A leg support and restraining device including a rod, a leg support pivotally mounted thereon, said support comprising a plurality of sections of substantially semi-circular cross-section, a sliding engagement between said sections, and means for locking said sections in adjusted positions. 5

4. A leg support and restraining device including a rod, a leg support pivotally mounted thereon, said support comprising a plurality of sections, a sliding connection between said sections, means for locking said sections in adjusted position, and supplemental means for securing the sections in operative position comprising a rod fixed to one section and adjustably connected to the other 10 section. 15

5. A leg support and restraining device including a rod, a leg support pivotally mounted thereon, said support comprising a plurality of telescopically connected sections, a secondary connection 20 between said sections including a rod, apertured lugs on the sections receiving the rod, and means for locking one of said sections in various adjusted positions along the rod. 25

6. A leg support and restraining device including a rod, a leg support pivotally mounted thereon, said support comprising a plurality of sections, a sliding connection between said sections consisting of elongated lugs formed on one section, elongated depressions formed in the other section and 30 slidably receiving the lugs, and set-screws for locking the sections in various adjusted positions. 35

7. A leg support and restraining device including a supporting rod, a leg support pivotally mounted thereon, said support comprising a plurality of sections, a sliding connection between said sections consisting of elongated lugs on one section, elongated depressions formed on the other section and slidably receiving the lugs, a guide rod 40 fixed to the exterior of one of the sections, one or more apertured lugs on the exterior of the other section and receiving an end of the guide rod, and means for clamping the lugs to the guide rod. 45
